UNITED STATES PATENT OFFICE.

AUGUSTE BLASER, OF CINCINNATI, OHIO.

COLUMN FOR BUILDINGS.

SPECIFICATION forming part of Letters Patent No. 360,134, dated March 29, 1887.

Application filed November 8, 1886. Serial No. 218,331. (No model.)

To all whom it may concern:

Be it known that I, AUGUSTE BLASER, a citizen of the United States, residing at Cincinnati, in the county of Hamilton and State of Ohio, have invented certain new and useful Improvements in Columns for Buildings; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in columns for buildings.

The object of my invention is to produce a column or post which can be adjusted lengthwise and used as a means for supporting depressed or overloaded floors in shops or factories, or in old or dilapidated buildings. It is also an object to make such columns as light as consistent with the materials employed, and with a view of making the columns plain or ornamental.

25 The column proper consists of a metallic "shaft," and either a metallic "capital" or "base" where there is provision for adjustment as to the whole length of the column, or 30 of a metallic shaft in connection with both a metallic capital and a metallic base, and where there is provision for longitudinal adjustment by making either or both the capital and base adjustable lengthwise of the shaft. The adjustability is provided by forming a thread at the end of the shaft and tapping either or both the capital and base, according to the construction preferred.

It is often necessary to temporarily strengthen 40 floors of warehouses or shops and factories in buildings having a number of stories, and where heavy machinery or materials are temporarily placed, and in large shops it is desirable, and sometimes necessary, to have as 45 much clear space as possible, and yet at times loads may necessarily be temporarily placed upon overhead floors which would be too great for the supporting-floor to stand, when it becomes necessary for the time being to support 50 the floor from below. Floors are often overloaded and depressed before any provision is

made for supporting them, when they must be raised to a level before or at the time props or posts are placed beneath them. In old or dilapidated buildings it is often desirable to level up 55 the depressed floors. Especially is this the case where such buildings are to be repaired for future use as shops or factories. Various expedients are resorted to in raising a floor preliminary to placing supports beneath it. 60

My improved adjustable column is intended for use in such places, and on account of its adjustability it serves as the tool for raising the depressed floor as well as the supporting-column. This is of great advantage in rooms 65 already filled with merchandise or machinery, &c., as in factories. The column is also especially adapted to be moved about within a given locality without taking it down, as may be desirable in construction-shops in providing 70 more room for the passage or setting up of large machinery.

For cheapness I prefer ordinary gas-piping for the shafts and castings for the capitals and bases.

75 The accompanying drawings show three modifications of my adjustable columns resting upon a floor, *f*, and supporting a ceiling, *c*, the right half of each being in mid-section.

Figure 1 shows a hollow shaft, 1, having a 80 capital, 12, supported by means of a nut, 11, screwed onto the exterior of the shaft and where the latter is screwed into and supported by a base, 21. Fig. 2 shows a similar shaft, 2, supported by and screwed into a base, 22, 85 and having a nut, 17, screwed onto its top and supporting a capital, 13, having a projection, 19, extending down into the end of the shaft. Fig. 3 shows a similar shaft, 3, supported by a base, 23, and having a capital screwed onto 90 its top.

The simplest modification is that shown in Fig. 3, where the shaft (piece of gas-pipe) 3 has a plain end, 10, resting within a corresponding recess in the base 23 and upon a flat 95 bearing, 24, belonging to the base. Here the upper end of the shaft 3 is threaded exteriorly at 9, and a hollow capital, 20, is tapped and screwed upon the threads 9, and is thus supported by the shaft. 100

In placing this column the capital is first screwed onto the shaft, so that the column may

be placed upright, after which the shaft may be rotated (by means of a pipe-wrench) until the capital bears against and supports the ceiling *c*.

- 5 In the modification shown in Fig. 1 the base 21 is hollow and tapped to receive the thread 5 on the lower end of the shaft 1. A nut, 11, is screwed upon the thread 4 at the top of the shaft, and the capital 12, which is hollow, fits 10 down around the end of the shaft and rests upon the upper surface of the nut 11. Here the base 21 may be put in place, the shaft 1 screwed into the base, the capital 12 placed over the top of the shaft and upon the nut 11, and the column adjusted so that the cap 12 will bear against the ceiling *c* and support it by turning the shaft 1 within the base 21, or by screwing up the nut 11, or by both operations.
- 20 In the modification shown in Fig. 2 the lower end of the shaft 2 has a thread, 7, which screws into the tapped base 22. The upper end of the shaft 2 has a thread, 6, onto which a circular nut, 17, screws, and the latter has an 25 enlarged upper end, 16, upon which the flange 15 of the capital 13 rests. The capital 13 may be hollow, as shown, and has a central part, 19, which extends down into and fits within the shaft 2. 14 represents ornamental parts 30 of the capital. In placing this modification the shaft 2 may be screwed into the base, the nut 17 screwed down upon the shaft, and the capital 13 placed over the shaft and lowered until the part 19 enters the latter and the flange 35 15 rests upon the enlargement 16, when the nut 17 or the shaft 2, or both, may be turned and the capital brought to bear against and support the ceiling *c*.

It is evident that various changes could be made in details without departing from the 40 spirit of my invention. For example, the lower end of the hollow shaft 3 could rest upon and around a corresponding part of a base, or it could be tapped and screwed onto the base. The upper end of the hollow shaft could be 45 tapped and the capital could have a part like the part 19 in Fig. 2, threaded and adapted to screw into the end of the shaft.

It is evident that a gas pipe could have a 50 tapped casting at one end only, and still answer all of the purposes of an adjustable column, as when it was screwed into a base and its upper end was placed against a beam.

The capitals, nuts, and bases may be made more or less ornamental; but for the use intended plain forms requiring the least amount of metal are preferable.

I claim—

1. In a column for buildings, a metallic shaft, in combination with a metallic capital, the 60 parts having male and female threads as means for longitudinal adjustment, substantially as and for the purposes set forth.
2. In a column for buildings, the combination of a metallic shaft, a suitable base, a nut, 65 and a capital, the nut screwing to the upper end of the shaft and the capital being formed to fit and be supported by the nut, substantially as set forth.

In testimony whereof I affix my signature in 70 presence of two witnesses.

AUGUSTE BLASER.
